L. A. MORTIMER.
SIGNALING SYSTEM.
APPLICATION FILED JULY 12, 1917.

1,384,398.

Patented July 12, 1921.

Inventor:
Louis A. Mortimer
J. E. Roberts Atty.

UNITED STATES PATENT OFFICE.

LOUIS A. MORTIMER, OF NEW YORK, N. Y., ASSIGNOR TO WESTERN ELECTRIC COMPANY, INCORPORATED, OF NEW YORK, N. Y., A CORPORATION OF NEW YORK.

SIGNALING SYSTEM.

1,384,398.

Specification of Letters Patent. Patented July 12, 1921.

Application filed July 12, 1917. Serial No. 180,145.

To all whom it may concern:

Be it known that I, LOUIS A. MORTIMER, a citizen of the United States, residing at New York, in the county of New York and 5 State of New York, have invented certain new and useful Improvements in Signaling Systems, of which the following is a full, clear, concise, and exact description.

This invention relates to signaling systems, and more particularly to non-interfering systems employing a single pair of line conductors for a plurality of purposes, as, for example, in composited telephone and telegraph working where it has been found 10 desirable to be able to signal an attendant at a telegraph repeater station, and to indicate which line conductor is concerned, without interfering with the use of the line for telephone and telegraph communication. On 15 busy and important lines, it is of the utmost importance to make any changes in the circuit, such as the cutting-in or cutting-out of a repeater, in the shortest possible time, and for this reason, it is important to be able to 20 signal the attendant sufficiently before the change is to be made to allow him to make all the necessary preparations therefor.

The objects of this invention are to provide a system wherein a signaling circuit 30 uses the same line conductors as are used for a composited telephone and telegraph circuit; to provide a signaling device for each line conductor which may be selectively energized, and to provide means for rendering 35 these signaling devices unresponsive to any of the sources of energy used in telephone and telegraph working, or to stray or transient currents which may gain access to the line conductors.

40 In accordance with one feature of this invention, an alternating current relay is simplex to a telephone circuit to control a selective signaling circuit, whereby one or another of a plurality of signaling devices 45 may be actuated, depending upon the nature of the received signaling current. In accordance with another feature, a second double-wound alternating current relay is bridged across the legs of the simplex circuit for disabling the signaling circuit when 50 telephone signaling current is impressed upon the line conductors, or when stray or transient currents find their way to the line conductors, due to irregular telegraph working 55 or other causes. Another feature of the invention is the use of a plurality of slow-

releasing relays in the signaling circuit, controlled by an alternating current relay, which is connected in simplex to the telephone circuit, whereby a single application 60 of signaling current, if not followed within a predetermined period of time by a second application of such current, will cause one of the signaling devices to be actuated; while two applications of such current, in succession, within such predetermined period of time, will cause the actuation of a second device.

This invention will be more clearly understood by reference to the drawing, which 70 illustrates diagrammatically one embodiment thereof.

In the drawing is shown a composited telephone and telegraph circuit having two telegraph stations A and B; at the former of 75 which is a source of signaling current and means to impress this current upon the line conductors and, at the latter, a selective receiving station with a plurality of signaling devices. Two telephone stations C and D, 80 with their associated signaling apparatus, are shown connected to either end of the line.

Two line conductors, 5 and 6, are shown extending between the telegraph stations A and B. Two telegraph operators' sets, 7 and 85 8, are represented at stations A and B, respectively, adapted to work with each other over line conductor 5; while two similar sets 9 and 10 are adapted to work over line conductor 6. As is common in composite telegraph practice each of these sets is connected to its respective line conductor and to ground through a retardation coil 11 and condenser 12 respectively. Condensers 13 90 isolate the various sections of the line, so far as telegraph impulses are concerned, while not disturbing the line continuity for telephonic transmission and signaling.

95 Signaling apparatus, comprising signal sending means 15, a selective receiving circuit 16 and a disabling circuit 17, are shown at station B; while, for the purpose of simplicity, only the signal sending apparatus 15 is shown at station A. All the apparatus in the drawing is shown in its normal quiescent condition.

100 It is believed that the invention will be clear from a description of its operation now to follow:

105 Let it be assumed that the attendant at station A wishes to inform the attendant at station B that the telegraph circuit em-

ploying line conductor 5 is to be concerned in some change. He can do this by actuating the signaling device or lamp 18. By actuating key 20, the attendant will impress 5 signaling current from generator 14 upon line conductors 5 and 6 in parallel to actuate an alternating current relay 19. The circuit for such current extends from ground at station A, lower engaged contact members (normally open) of key 20, generator 14, then 10 in parallel paths over the line conductors 5, 6 to winding 22 of relay 19; one path extending through upper engaged contact members (normally open) of key 20, upper 15 left-hand retardation coil 11 and condenser 13 at station A, line conductor 5, condenser 13 and upper right-hand retardation coil 11 at station B, condenser 25, upper normally engaged contact members of key 26, 20 normally engaged contact members 28, 29 of relay 30 and resistance 31; the other extending from intermediate engaged contact members (normally open) of key 20, lower left-hand retardation coil 11 and condenser 25 18 of station A, line conductor 6, condenser 13 and lower right-hand retardation coil 11 of station B, condenser 34, intermediate normally engaged contact members of key 26, 25 normally engaged contact members 37, 38 30 of relay 30 and resistance 32; thence through windings 22 and 39 of relay 19 to ground. The condensers 12 are of such capacity that the leakage through them is not of a sufficient amount to prevent the operation of 35 relay 19 since this relay is of a very sensitive high resistance type and therefore responds to an exceptionally low value of current. The operation of relay 19 opens the circuit of normally energized relay 40, 40 allowing its armature 41 to be retracted, thereby disengaging contact member 42, and causing the engagement of contact members 42 and 43. Relay 44 is thereupon energized over a circuit from battery 45, normally engaged contact members of relay 45 48, winding of relay 44, engaged contacts 43, 42 of relay 40, engaged contact members of locking key 49 to ground. The actuation of relay 44 causes the engagement 50 of contact members 50, 51, and the disengagement of contact members 51, 52. Upon the removal of signaling current from the circuit at station A, relay 40 is again energized to cause the engagement of contact 55 members 41, 42 and to disengage contact members 42, 43. Relay 48 is thereupon energized over a circuit from battery 45, winding 53 of relay 48, engaged contact members 50, 51 of relay 44, engaged contact members 41, 42 of relay 40, through the engaged contact members of locking key 49 to ground. Its armatures are thereupon attracted; the lower serving to interrupt the energizing circuit of relay 44 by 60 65 disengaging the normally engaged back con-

tact member and to partially prepare an energizing circuit for relay 56 by engagement with the lower alternate contact member; the upper serving to close a locking circuit for relay 48 and to light lamp 18. 70 The locking circuit for relay 48 may be traced from battery 58, upper engaged contact members (normally open) and winding 60 of relay 48, through engaged contact members of locking key 49 to ground. The 75 lamp 18 is energized over a circuit from battery 58, upper engaged contact members (normally open) of relay 48, upper normally engaged contact members of relay 56, lamp 18, engaged contact members 52, 80 51 of relay 44, and engaged contact members 41, 42 of relay 40, through engaged contact members of locking key 49 to ground. It is to be noted that relay 48 cannot be energized until relay 40 has again 85 become energized, and that lamp 18 cannot be lighted until relay 44 has been deenergized. Relay 44 being a slow release relay, it is thus evident that a predetermined 90 period of time will elapse between the deenergization of relay 19 and the lighting of lamp 18, depending upon the time it takes for relay 44 to release its armature. Lamp 18 is therefore lighted by a single application 95 of signaling current at station A. 95

In order to indicate that line conductor 6 is also concerned, the attendant may actuate signaling device or lamp 63. A second application of signaling current will cause the deenergization of lamp 18 and 100 the actuation of lamp 63 in a way now to be described.

Such second application of signaling current will again cause the deenergization of normally energized relay 40, as hereinbefore 105 described, causing the actuation of relay 56 over a circuit from battery 45, lower alternate contact members of relay 48, winding of relay 56, engaged contacts 43, 42 of relay 40, engaged contact members of locking key 49, to ground. The actuation of relay 56 interrupts the energizing circuit 110 of lamp 18 by causing the disengagement of its upper normally engaged contact members, and completes an energizing circuit for lamp 63 from battery 64, lamp 63, alternate engaged contact members of relay 56, engaged contact members of locking key 49, to ground. Relay 56 is locked up as a result of its actuation, since the energizing 115 circuit of relay 40 is thereby interrupted, causing the continuous engagement of contact members 42, 43 thereof; the normally closed energizing circuit of relay 40 extending from battery 67, winding of relay 40, 120 normally engaged contact members of relay 19, lower normally engaged contact members (now open) of relay 56, engaged contact members of locking key 49, to ground. 125

Again, in order to indicate that line con- 130

ductor 6 alone is concerned, lamp 63 alone may be actuated by two successive applications of the signaling current within a predetermined period of time determined by 5 the time of release of relay 44. Until relay 44 has released its armature 50, the circuit of lamp 18 is interrupted at contact members 51, 52 of relay 44, but relay 48 has already been locked up by the subsequent energization of relay 40 to prepare the energizing circuit of relay 56 by causing engagement of the alternate contact members 10 of relay 48. Therefore, while the first application of signaling current will not actuate the lamp 18 within the above mentioned predetermined period of time, a second application, occurring within that time, will cause lamp 63 to be lighted in the manner hereinbefore described.

20 The attendant at station B can return all apparatus of the circuit to normal by the disengagement of the contact members of locking key 49, thereby removing the ground connection of each of the relays.

25 In order to prevent the system from giving false signals, due to the signaling current from the telephone system or due to stray or transient currents on the telephone lines, which may find their way to ground 30 through relay 19, a second alternating current relay 70 is provided, having a pair of normally engaged contact members and having its windings 73, 74 connected in series aiding across points of equal potential in the 35 two legs of the signaling circuit, hereinbefore described. Such currents, by causing the energization of relay 70, will deenergize relay 30 to disconnect the signaling circuit from the line conductors by the disengagement of contact members 28, 29 and 37, 40 38 of relay 30. The energizing circuit of relay 30, which is interrupted by the disengagement of the normally engaged contact members of relay 70, extends from battery 75, winding of relay 30, normally engaged contact members of relay 70, to ground.

In the preferred embodiment of this invention, the source of signaling current 14 is adapted to furnish current of approximately 133 cycles per second; the relays 19 and 70 being adapted to respond to current of substantially the same frequency.

It is, therefore, seen that the attendant at station A can cause the actuation of either 55 of the lamps 18 or 63. He can do this without interfering with the telegraph communication between telegraph sets 7 and 8 or 9 and 10, because the telegraph instruments are not responsive to signaling current from 60 generator 14, and without interfering with telephonic communication or signaling between telephone stations C and D, since his signaling current traverses the telephone line conductor in parallel. His own sig-

naling devices, moreover, are not affected by either of those agencies, or by false or transient currents which may find their way upon the line conductors; due principally to the fact that relay 19 is responsive only to currents of frequency substantially the same as that of his signaling current, but also to the fact that his signaling devices are disconnected from the line conductors by the actuation of relay 70 in other instances where false signals might be given.

75 What is claimed is:

1. In a signaling system, a plurality of signaling devices, a source of signaling current, a relay responsive to a single application of current from said source, means operative due to the energization of said relay to actuate one of said signaling devices and to condition another of said signaling devices for operation and responsive due to a second energization of said relay by 80 current from said source to disconnect the first-mentioned signaling device and to actuate the other signaling device.

2. In a signaling system, a plurality of signaling devices, an operating circuit for each of said devices, a source of signaling current, means responsive to a single application of current from said source to actuate one of said signaling devices and partly establish the operating circuit for another 90 of said signaling devices and responsive to two successive applications of current within a predetermined length of time to disconnect the first mentioned signaling device and to complete the operating circuit of the 95 100 other signaling device.

3. In a signaling system, a plurality of signaling devices, an operating circuit for each of said devices, a source of signaling current, means responsive to a single application of current from said source to select 105 and actuate one of said signaling devices and partly establish the operating circuit for another of said devices, and a relay co-operating with said means in response to two successive applications of current within a predetermined period of time to disconnect the first mentioned signal and to select and complete the operating circuit of the other of said signaling devices.

115 4. In a signaling system, a plurality of signaling devices, a source of signaling current, signal-control means adapted to be actuated by said signaling current, other means actuated by a single energization of 120 said signal-control means to operate one of said signaling devices, still other means co-operating with said beforementioned means actuated by a second energization of said signal-control means to operate another of 125 said signaling devices, and a relay co-operating with said other means to prevent the operation of said first mentioned signaling

- device if the second energization of said signal-control means occurs within a predetermined period after the first energization thereof.
5. In a signaling system, a plurality of signals, a source of signaling current, a signal-control means adapted to be energized by said signaling current, a relay actuated by a single energization of said signal-control means to actuate one of said signals, a second relay actuated by said single energization of said signal-control means to delay the actuation of said signal for a predetermined length of time, and a third relay coöoperating with said first mentioned relay adapted upon a second energization of said signal-control means to actuate another of said signals.
6. In a signaling system, a pair of line conductors, signaling apparatus connected to said line conductors and a source of signaling current adapted to supply current in parallel over said line conductors to actuate said signaling apparatus, another source of current adapted to supply current in series over said line conductors, and means responsive to said series current to disconnect said signaling apparatus from said line conductors.
7. In a signaling system, a pair of line conductors, signaling apparatus connected to said line conductors, a source of signaling current adapted to supply current over said line conductors for actuating said signaling apparatus, sources of current other than said source of signaling current adapted to supply current over said line conductors, and means actuated by said last mentioned currents to disconnect the signaling apparatus from the line conductors.
8. In a signaling system, a pair of line conductors, signaling apparatus connected to said line conductors, a source of signaling current adapted to supply current in parallel over said line conductors for actuating said signaling apparatus, another source of current adapted to supply current over said line conductors in series, a relay responsive to said series current, and a second relay adapted to disconnect the signaling apparatus from said line conductors upon the actuation of said first mentioned relay.
9. In a signaling system, a plurality of line conductors, signaling apparatus connected thereto, a plurality of sources of current having different electrical characteristics adapted to supply current over said line conductors, means connected to but intermediate said signaling apparatus and said line conductors responsive to current from one of said plurality of sources to disconnect said signaling device from said line conductors but unresponsive to current from another of said plurality of sources.
10. A signaling system comprising a plurality of signaling devices, a source of signaling current, means responsive to a single application of current from said source to actuate one of said signaling devices and to condition another of said signaling devices for operation and responsive to two successive applications of current within a predetermined period of time from said source to prevent the operation of the first mentioned signaling device and to actuate the other signaling device.

In witness whereof, I hereunto subscribe my name this 9th day of July, A. D. 1917.

LOUIS A. MORTIMER.
